ABSTRACT

Metalliferous vapors are condensed on an ebulliently cooled heat-conducting wall member of a heat exchanger. The metalliferous vapor comprising the vapors of an aluminum halide and an alkali metal or alkaline earth metal are condensed to produce two immiscible liquid phases of aluminum and an alkali metal, or alkaline earth metal, halide respectively. The temperature of the ebullient liquid is controlled by regulating the composition of the ebullient liquid, the pressure over it or both. Preferably the wall member is constructed of a material which is preferentially wet by the molten alkali metal or alkaline earth metal halide relative to molten aluminum. Accordingly, erosion of the salt-wet wall member by liquid aluminum is substantially reduced. Preferred ebullient liquids include alloys of copper and magnesium or zinc and magnesium chloride. Any of these materials would safely mix with liquid aluminum and the alkali metal or alkaline earth metal condensate in the event of catastrophic failure of the heat exchanger walls.

EBULLIENT COOLING OF HIGH TEMPERATURE METALLIFEROUS VAPORS

This is a continuation of application Ser. No. 851, filed Jan. 6, 1970 and now abandoned.

A method for the recovery of aluminum from impure sources of the metal is described in U.S. Pat. No. 3,397,056. In one phase of the process therein described, a mixture of aluminum halide vapor and an alkali metal, or alkaline earth metal, vapor is condensed to recover a purified aluminum and reconstituted alkali metal or alkaline earth metal halide. Although such a condensation reaction is readily accomplished on any heat transferring surface below the dew point of the vapors, serious problems of erosion and strength deterioration occur in most materials of construction after prolonged used.

In addition, because of the high temperatures and heat fluxes involved, satisfactory large scale condensers must be capable of rapidly removing heat under highly variable conditions of operation.

In view of the above desiderata of the art, it would be advantageous, and it is a particular object of the instant invention to provide a new method for condensing metalliferous vapor systems as herein defined, i.e., $A_1X + M$ representing respectively aluminum halide and an alkali metal or alkaline earth metal vapor.

A particular object is to provide an improved method for condensing the described metalliferous vapors with the capability of removing large heat fluxes under conditions of varying vapor temperature and mass flow rates.

Another object is to provide an improved method for condensing the metalliferous vapors whereby erosion of heat exchanger construction materials is minimized and equipment life is extended.

A still further object is to provide a condensing system for the described metalliferous vapors in which the temperature of the cooling surface is regulated. A particular object in the latter regard is to provide an improved cooling system in which the composition of an ebullient liquid is regulated to adjust cooling temperatures.

Another object in the latter regard is to provide an ebullient cooling method in which the temperature is regulated by the pressure maintained on the ebullient liquid.

Pursuant to the above objectives, and in accordance with the instant invention, an improved process for cooling metalliferous vapors comprises the following steps: Metalliferous vapors are contacted with a heat exchanging surface of a wall member of a heat exchanger, which at least partially defines wall encloses a condensation zone. A second surface of the wall member is cooled with an ebullient liquid. The latter is characterized by boiling temperature below the condensation temperature of the metalliferous vapors but above the melting point of aluminum. Heat absorbed by the ebullient liquid is transmitted by vapors of the ebullient liquid to a secondary heat exchanging means. The vapors of the ebullient liquid are thus condensed and returned to the body of ebullient liquid.

Metalliferous vapors to which the invention is generally applicable are characterized by the symbols $A_1X + M$ wherein A_1X is one or more aluminum halides, e.g., aluminum monofluoride, aluminum trifluoride, aluminum monochloride, aluminum trichloride and M is a metal of Groups I and II, e.g., an alkali metal and

alkaline earth metals. In a preferred embodiment, the invention is applied to a vapor system comprising aluminum monofluoride and magnesium, which upon condensing produces aluminum and magnesium fluoride as liquid. This reaction is further elaborated in U.S. Pat. No. 3,397,056.

It is an essential characteristic of the foregoing method that the temperature of the condensing surface be controlled within limits, which on the upside are sufficiently low to achieve the desired condensation and heat removals from incoming vapors and which at the lower end are sufficiently high to be above the melting point of the condensate products, i.e., aluminum and an alkali metal or alkaline earth metal halide. Accordingly, temperature control in the ebullient fluid is an essential and most significant aspect of the instant invention. In the drawings:

FIG. 1 is a schematic illustration of the application of ebullient cooling in accordance with the instant invention. A special modification of the apparatus equalizes pressure within the ebullient system with that in the condensing zone.

FIG. 2 depicts a condensing, tube-type, heat-exchanger with ebullient liquid within the tubes and means for continuous aluminum and salt by-product take off.

By reference to FIG. 1, the process of the instant invention is illustrated by condensing aluminum fluoride and magnesium vapors within a condensation zone 10 defined by condenser housing 11 having a vapor inlet 27. Within the product condenser housing 11 is an ebullient liquid housing 12 having a condensing surface 13. Heat is absorbed by the ebullient liquid 16 thereby condensing aluminum and magnesium fluoride 15 on the condensing surface 13. The condensing surface 13 is preferably made of a material which is preferentially wet by the magnesium fluoride relative to liquid aluminum. The condensed liquid aluminum and magnesium fluoride 15 drain through downpipe 28 into a product coalescing vessel 20, in which they separate by gravity into essentially pure liquid phases of aluminum 25 and magnesium fluoride 24. Each of these products is withdrawn, either continuously or intermittently, as they are accumulated, through outlets 22 and 23, respectively.

Vapors from the ebullient liquid 16 rise in vapor zone 9 to contact the heat exchanging coil 14 where they are condensed and ultimately returned to the body of the ebullient liquid 16. The vapor zone 9 above the ebullient liquid communicates by means of conduit 18 with the vapor zone above the condensate in collection vessel 20. Within conduit 18 is an on-off valve 17 and a gas discharge vent with valve 19. An inert gas 31 is connected to the conduit 18 through pressure valve 29.

In the preferred mode of operation, the system is operated at a given pressure, which is equilibrated in zones 9 and 10 by maintaining valve 17 in an open position and valve 29 closed. Pressure regulating valve 19 is set to control at the desired operating pressure. This system provides direct pressure communication between the ebullient boiling vapor zone 9 and the vapor zone 10 of the product condenser housing 11. In the event the noncondensable gas pressure over the ebullient liquid significantly exceeds that within the condenser housing 11, the pressure differential will be reduced by pressure release into the condenser housing 11 through the condenser downpipe 28. Alternatively,

should pressure within the condenser housing 11 exceed that in zone 9, the pressure flow will reverse. The continuous withdrawal of aluminum and magnesium fluoride from the condensate collection vessel 20 assures desired liquid levels of these two products.

A principal benefit of operating in the foregoing manner is that the pressure within the ebullient liquid housing is equalized with that within the condenser housing. This minimizes stresss on the heat conducting wall members of the ebullient liquid housing 12.

In an optional variation, valve 17 may be closed and tempearture regulation of the ebullient liquid 16 achieved by controlling the noncondensable gas pressure in vapor zone 9. This is achieved by regulating the supply of inert gas 31 by means of pressure regulating valve 29 and pressure regulating gas vent 32. Whenever a lower boiling temperature is required in the ebullient liquid, as for example when the heat flux entering the condenser is high, the temperature of the ebullient liquid is lowered by releasing pressure in the vapor zone 9 through valve 32. When a higher temperature in vapor zone 9 is necessitated by a lower heat flux, valve 32 is adjusted to regulate at a high pressure and an inert gas supply is administered to the vapor zone 9 through valve 29.

FIG. 2 illustrates another embodiment of the invention in which aluminum halide and metal vapors enter a condenser housing 40 through vapor inlet 42. Within the housing is a tube bundle 51 of individual tubes 52 fitted into tube headers 50 and 54. The tube bundle 51 defines, in conjunction with the interior walls of the condenser housing 40, a condensation zone 41. This zone is occupied, during operation with incoming vapors and condensed liquid phases of aluminum 61 and metal halide 60. The liquid aluminum 61 is discharged through outlet 46 containing a trap equipped with a noncondensable gas vent 45. The metal halide 60 is discharged as a liquid through discharge port 44. Below the tube bundle header 50 is located a reservoir 49 of an ebullient liquid 65a, which can be, for example, a copper-magnesium alloy. Within this reservoir 49 are a special resistance heating means 47, 47a to maintain the ebullient liquid above its liquidus temperature. In the lower portion of the heat exchanger housing 40 there is also a drain 48 from which accumulations of non-volatile residuals may be removed periodically from the reservoir 49.

The upper tube header 54 defines in conjunction with the condenser housing 41 a vapor zone 63 above which there are condensing means 53 for condensing the vapors 65a of the boiling ebullient liquid 65b. The condensate 65d returns to the boiling ebullient liquid. The illustrated condensing means 53 is simply a steam cooled tube heat exchanger.

The vapor zone 63 is adapted at port 56 for the removal of vapors of the ebullient liquid. These vapors may be condensed by means not shown and recycled at port 55.

In one mode of operation, temperature control is achieved by regulation of pressure on the ebullient liquid. By either introducing or withdrawing a noncondensable gas over the ebullient liquid, its boiling temperature may be increased or decreased as is necessary to maintain the condensing surface at a suitable temperature.

Although pressure control is a feasible mode for regulating the temperature of an ebullient system and thus

the temperature of the condensing surface of the present invention, the engineering of satisfactory equipment in which to carry out the process is complicated by the requirement of high strengths at high temperatures in construction materials.

It is a preferred mode of operation to employ, as the ebullient liquid, a material which is characterized by the desired boiling temperature for ebullient cooling or is readily adjustable to provide such a boiling temperature. In the latter regard, a satisfactory ebullient liquid comprises two materials having significantly different vapor pressures and at least one of these materials boils at a temperature below that necessary to achieve condensation in the instant invention. In such a system, the more volatile component vaporizes preferentially to the less volatile component. If the entire condensate of such vapors is returned to the body of ebullient liquid, an equilibrium is quickly established and the temperature of ebullient liquid controlled to a constant level determined by the composititon of the liquid.

In the event increases in the boiling temperature of the ebullient liquid are desired, a portion of the vapors is condensed and withdrawn from the boiling system thereby relatively increasing the proportion of the higher boiling component and thus the temperature of the ebullient liquid. Similarly, the introduction into the body of ebullient liquid of additional amounts of a lower boiling ebullient liquid component reduces the temperature on the system.

Alloy mixture of the volatile metals such as magnesium, zinc and bismuth with one or more less volatile or stable metals such as copper, lead, tin or silver are suitable for use as an ebullient liquid in the aforescribed controlled system. Salt mixtures which can be similarly employed include, for example, mixtures of volatile salts such as magnesium chloride, lead chloride and sodium chloride with less volatile salts such as calcium chloride, calcium fluoride and magnesium fluoride.

Utilizing the foregoing, a method is provided for condensing the metalliferous vapors described above in which heat flux is controlled by the temperature differential across the heat exchanging wall and thus temperatures are maintained within necessary and desirable limits.

In the practice of the invention, the heat-conducting wall member of the heat exchanger is either manufactured of, or surface clad with, a material which is wetted preferentially by an alkali metal or alkaline earth metal salt relative to liquid, molten aluminum. This preferential wetting is important to the ultimate protection of the heat exchanger surface from molten aluminum which is extremely corrosive. Materials of construction possessing the desired wettability characteristics with respect to the two phase liquid-liquid condensates produced in accordance with the invention include the borides, nitrides, and carbides of aluminum, silicon, titanium and zirconium and boron carbide or nitride. Examples are graphite, aluminum nitride, aluminum carbide, zirconium carbide, titanium carbide, silicon carbide and boron nitride.

In a special embodiment, the ebullient fluid is selected of a material having a desired boiling point and this material is purified by continuous distillation. In such event, the material is substituted for the ebullient liquid and the distillation allowed to proceed with the recovery of condensate to produce the desired purified

product. Illustratively, magnesium chloride boils at a temperature which is generally suitable for cooling the inside surface of the heat conducting wall member. Accordingly, it is possible to continuously distill and purify magnesium chloride, while condensing the metalliferous vapors to produce aluminum and magnesium fluoride according to the teachings of U.S. Pat. No. 3,397,056.

What is claimed is:

1. A process which comprises
1. contacting condensable AlF + Mg vapors, with a first surface of a heat conducting wall member in a condensation zone to produce a condensate containing distinct molten phases of aluminum and magnesium fluoride,
2. cooling a second surface of the wall member with an ebullient liquid in heat exchange relation with the wall member, said liquid characterized by a boiling temperature, under extant conditions, below the condensation temperature of the metalliferous vapors in the condensation zone but above the melting point of aluminum and said ebullient liquid being selected from the group consisting of magnesium chloride or a molten alloy of magnesium, bismuth or zinc with one or more members of the group consisting of copper, lead, tin and silver.
2. A method as in claim 1 wherein the first surface of the heat conducting wall member is preferentially wet by the magnesium fluoride relative to molten alumi-

num.

3. A method as in claim 1 and including the additional step of increasing or decreasing the pressure on the ebullient liquid to correspondingly increase or decrease its boiling temperature.

4. A method as in claim 3 wherein the extent of pressure increase or decrease is controlled relative to the amount of incoming vapors to maintain the heat flux across the heat conducting wall member at a level sufficient to condense the AlF + Mg vapors, but without solidifying either condensate phase.

5. A method as in claim 1 wherein the ebullient liquid is a composition comprising two materials having significantly different boiling temperatures, at least one of these materials being further characterized by having a boiling temperature below the condensation temperature of the vapors and both materials characterized by having a melting point below such condensation temperature.

6. A method as in claim 5 wherein the ebullient liquid is a mixture of magnesium and copper.

7. A method as in claim 5 wherein the temperature of the ebullient liquid is controlled to a desired level by adjusting the relative ratio of the two materials in the ebullient liquid.

8. A method as in claim 7 wherein the ratio is adjusted by distilling off the more volatile component from, or returning the same to, the ebullient liquid.
